UNITED STATES PATENT OFFICE.

JOSEPH HOTCHNER, OF PROVIDENCE, RHODE ISLAND.

SIGN.

SPECIFICATION forming part of Letters Patent No. 768,179, dated August 23, 1904.

Application filed February 15, 1904. Serial No. 193,702. (No model.)

To all whom it may concern:

Be it known that I, JOSEPH HOTCHNER, a citizen of the United States, residing at Providence, in the county of Providence and State of Rhode Island, have invented certain new and useful Improvements in Signs; and I do declare the following to be a full, clear, and exact description of the invention, such as will enable others skilled in the art to which it applies to make and use the same.

My invention relates to improvements in signs, and more particularly in sign letters or characters and the means for securing them upon the sign-board or background.

One of the objects of my invention is to provide a fastening means for the sign letters or characters which will hold them away at a distance from the sign-board or other background, so as to cause them to throw a natural shadow upon the sign-board, and thereby present an attractive and novel appearance.

Another object of my invention is to provide a fastening means of this character which will permit the letters or characters to be readily attached to and detached from the background or sign-board without injury to the letters and which when the letters are applied will be entirely hidden from view.

Another object of my invention is to improve and simplify the construction of devices of this character, and thereby render them more attractive and durable in use and less expensive to manufacture.

With these and other objects in view the invention consists of certain novel features of construction, combination, and arrangement of parts, as will be more fully described, and particularly pointed out in the appended claims.

In the accompanying drawings, Figure 1 is a perspective view of a portion of a sign-board with one of my improved letters secured thereto in accordance with my invention. Fig. 2 is a sectional view through the same, taken on the line 2-2 of Fig. 1. Fig. 3 is a perspective view of one of the holding devices before the same is applied to the sign-board or base. Fig. 4 represents several detail sectional views through letters or characters of

slightly-different forms from that shown in 50 the other figures of the drawings.

Referring to the drawings by numerals, 1 denotes a sign-board or base which may be of any suitable material and constructed in any desired manner.

2 denotes my improved letters or characters, and 3 denotes my improved means for fastening the said letters or characters upon the said sign-board. The letters or characters 2 are hollow and open at their backs, as shown, 60 being molded, cast, stamped, or otherwise formed of metal, rubber, fiber, glass, or any other material which when finished has a smooth hardened surface.

While I do not confine myself to the use of 65 any particular material, I prefer to employ vulcanized fiber, rubber, or any plastic material capable of being molded and pressed and which is very light in weight, durable, and when hardened has a smooth finished surface 70

capable of being gilded or otherwise ornamented without requiring painting or other treatment. In cross-section the letters or characters may be of any desired configuration.

Their fronts 4 are preferably made flat, angular, or curved, as indicated in Fig. 4, and their sides 5 are formed at suitable intervals 75

with pairs of openings or apertures 6, into which tongues 7 upon the fastening devices 3 project to secure the letters or characters 80 thereto. Each of the said fastening devices

3 consists of a piece of flat steel bent, as shown in Fig. 3, to form a curved central portion 8 with a substantially right-angular-shaped portion 9 at each of its ends, and then it is tem- 85

pered to give it sufficient spring or resiliency to retain the letters or characters 2. The retaining-tongues 7 are formed, preferably, by cutting the outer ends of the right-angular-shaped portions 9 and bending a portion out- 90

wardly, as shown. The curved central portion of each fastener is formed at its center with two openings or apertures 10, through which a staple 11 or any other suitable fastening device is passed to secure it to the sign- 95

board or base 1, as clearly indicated in Fig. 2. These fasteners 3 are secured upon the sign-board at intervals corresponding to the inter-

vals or spaces between the pairs of openings 6 in the sides 5 of the sign letters or characters.

The manner in which the letters or characters are applied to and removed from the fastener after the latter have been secured to the sign-board will be readily seen upon reference to Fig. 2 of the drawings. When it is desired to attach the letters or characters, the ends of the fasteners are bent up one at a time until the tongues 7 spring into the openings 6, and when it is desired to remove them the ends of the fasteners are pressed inwardly until the tongues 7 are disengaged from said openings 6. It will be observed that owing to the shape of the fasteners 2 the letters will be held firmly and securely at a distance from the sign-board or background, and the means of attachment of the letters will be almost entirely hidden.

In the accompanying drawings I have illustrated but one letter or character, that being the letter "L;" but it will be understood that letters, numerals, symbols, and characters of any description may be similarly attached to a background or base. It will be further understood that various changes in the form, proportion, and the minor details of construction may be resorted to without departing from the principle or sacrificing any of the advantages of this invention.

30 From the foregoing description, taken in connection with the accompanying drawings, the use and advantages of my invention will be readily understood without requiring a more extended explanation.

35 Having thus described my invention, what I claim as new, and desire to secure by Letters Patent, is—

1. A fastener for sign letters or characters comprising a spring-bow, and means for securing the ends of the bow under tension to a sign, substantially as described.

2. The combination of a support, a bow secured intermediate its ends to the support, and a sign letter or character secured to the ends of the bow and held by the bow spaced from the support, substantially as described.

3. In combination, a hollow raised sign letter or character and a fastener therefor comprising a spring-bow sprung into the sign and fastened at its ends thereto, substantially as described.

4. A fastener for sign letters or characters consisting of a strip or plate of spring metal having a curved central portion formed with apertures and having right-angular-shaped

portions at each end, the outer ends of said right-angular-shaped portions having bent retaining-tongues, substantially as described.

5. The combination of a support, a sign letter or character, and a bow fastened intermediate of its ends to the support and at its ends to the sign letter or character, the said intermediate portion of the bow projecting beyond said letter or character to hold the same spaced from said support, substantially as described. 60

6. A hollow raised sign letter or character having a fastener-spring therein and secured thereto, substantially as described.

7. A hollow raised sign letter or character having an attaching-flange, a spring-bow having rearwardly-bent ends bearing against said flange, and means for fastening the bent ends of the bow to said flange, whereby the bow is doubly secured by its spring action and the fastenings, substantially as described. 70

8. A sign letter or character having attaching portions, a spring-bow having its ends bearing with pressure against said attaching portions, and means for securing said attaching portions to the ends of the bow, substantially as described. 80

9. A sign-fastener comprising a spring-bow, and means for attaching a sign to the ends of the bow, substantially as described.

10. A sign letter or character having attaching portions, and a spring-bow having its end portions sprung into engagement with said attaching portions, whereby the bow is held under tension, and means for attaching the ends of the bow to said attaching portions, substantially as described. 85

11. A sign-fastener comprising a bow having attaching ends outwardly and rearwardly bent, and means for attaching the rearwardly-bent portions of the ends of the bow to a sign, substantially as described. 95

12. A sign-fastener comprising a bow having attaching ends outwardly and rearwardly bent, the rearwardly-bent portions of the ends of the bow being provided with retaining-tongues to hold the same in engagement with a sign, substantially as described. 100

In testimony whereof I have hereunto set my hand in presence of two subscribing witnesses.

JOSEPH HÖTCHNER.
